PHOTOELECTRIC-CONTROLLED GAS-
DISCHARGE TUBE

Edward Charles Dench, South Orange, N. J.

Application March 2, 1940, Serial No. 321,936

3 Claims. (Cl. 250—41.5)

The present invention relates to discharge devices, and more particularly to devices of this character controlled by photoelectric action.

An object of the invention is to provide a new and improved electrical controlling device of the discharge type that is controlled by the action of light or other radiant energy.

Another object is to provide a new and improved thermostatic or thermally-sensitive controlling device controlled through the photoelectric control of the flow of electrons, or ionization, within the tube, which flow or ionization, in turn, communicates heat to the thermally-responsive element or elements.

Still another object contemplates the use of a tube of the above-described character containing at least one electrode in addition to the thermostatic or thermally-responsive element or elements.

A further object is to provide a new and improved photoelectric relay, operating on the thermal principle, and that shall be simple and compact in construction and operation, and inexpensive to manufacture and operate.

Other and further objects will be explained hereinafter and will be particularly pointed out in the appended claims.

The invention will now be more fully explained in connection with the accompanying drawing, in which Fig. 1 is a diagrammatic view in section, of a tube embodying the invention, shown connected in a circuit illustrative of an intended use; and Fig. 2 is a similar view of a modification.

The tube envelope, container, or lamp 11 may contain gas, vapor, or other substance, or a combination of the same, providing a readily ionizable medium at an optimum pressure below atmospheric. A suitable such gas is neon. According to a feature of the present invention, the tube 11 is provided with at least one electrode in addition to a thermostatic or thermally-responsive element or elements. The electrodes are normally spaced in the container a predetermined distance from one another. The thermally-responsive element is shown as a photo-sensitive cathode 413 or 513, constituted of a bimetal strip coated with a photo-sensitive electron-emitting material. The photo-sensitive material may, for example, be caesium oxide on silver, which is capable of emitting electrons under the action of radiant energy. The cathode 513 is shown fixedly supporting at its free end a contact member 15, and the cathode 413 a contact member 415. The tube 11 is shown provided also with an anode 417 or 517, with or without a grid or other control electrode 516, and

an electrode member 412 or 512 for supporting a cooperating contact member 414 or 14. The bimetal should be so designed that, upon a rise in its temperature, it shall flex to such position that the contact member 15 shall engage the contact member 14, or the contact member 415 shall engage the contact member 414, for the purpose of closing an electric circuit. The contact members 14 and 15 or 414 and 415 are designed to carry a comparatively large current. They need not be the simple ones shown; any combination of make-and-break contact members, operated directly or indirectly by thermal action, as hereinafter described, may be used.

15 The grid 516 may be constituted of solid material of any shape, although a mesh or perforated plate is preferred. The grid need not be disposed as shown; it may surround either the anode or the cathode. The anode 417 or 517, which may be 20 of simple construction, is so situated in the tube 11 that it shall not interfere badly with rays of light impinging on the cathode 413 or 513.

The tube is shown so connected into circuit that a positive potential is impressed upon the anode 417 or 517, sufficient to maintain a gaseous discharge in the tube, and the grid 516 (where employed) is so biased, through an impedance 21, that the discharge is normally restrained from taking place. The cathode bimetallic strip 513 25 is shown connected in circuit with a resistor or potentiometer 19, supplied with energy from a battery 20, and a ballast resistor or other impedance element 18 to the anode 517, so as to impress a potential upon the anode 517 positive with respect to the cathode. The anode 517 is connected, through the resistor 18, to the positive side of the resistor 19, the cathode 13 is adjustably connected to the negative side of the resistor 19, and the grid 516 is connected, through the 30 impedance 21, to an intermediate point of the resistor 19. A suitable potential is thus impressed upon the grid 516, the value of which may be varied, by varying the connection of the grid 516 to the resistor 19, to cause the grid to control the 35 flow and the energy of the electrons between the cathode 13 and the anode 517. In this manner, it is possible to permit the electrons to have sufficient energy to ionize the neon or other gas in the tube.

40 The cathode 413 or 513, carrying the contact member 415 or 15, may be connected to a binding post 318, and the member 412 or 512, carrying the contact member 14, to a binding post 319. The binding posts 318 and 319 may be connected 45 to any desired external electric circuit or circuits,

the closing (or opening) of which it is desired to control by the closing (or opening) of the contact members 14 and 15. Such external electric circuit may, for example, contain any desired load (not shown) in series with a source of energy (not shown). The cathode electrode 413 or 513 may be connected, through the binding post 318, to the energy source (not shown), and the electrode 412 or 512, through the binding post 319, to the load (not shown).

Assuming light rays or other radiant energy to fall upon the photo-sensitive cathode 413 or 513, electrons will be released therefrom, which will be attracted to the more positive anode 417 or 517. This electron current will produce a voltage drop on the impedance 21 (in the circuit of Fig. 2), resulting in a potential change of the grid 516. The pressure of the ionizable medium in the envelope 11 is of such value that this voltage change will effect a glow discharge between the anode electron 517 and the cathode electrode 513. If the potentiometer or other grid-bias source has been suitably adjusted, bombardment of positive gas ions upon the cathode will result in heating the bimetal strip 513 of the cathode. The bimetal strip will thereupon flex to effect closing, through the medium of the contact members 14 and 15, of the electric circuit connected to the binding posts 318 and 319. A thermostatically operated switch 14, 15 is thus provided, under the control of a photo-sensitive cathode 513, that controls the gas discharge the action of which controls the heating of the thermostatic device.

Once thus closed, the circuit will remain closed, and the relay will operate, independently of the grid, very much as takes place in a grid-glow tube. By appropriate means, however, the grid may be caused to stop the discharge. By energizing the tube from an alternating-current source of energy, for example, the discharge will stop at each zero point of the cycle, thus permitting the grid to regain control.

A tube of the described nature has many applications where an electrical circuit needs to be closed in response to the action of light or radiant energy. It is very simple, cheap and efficient, and it is capable of carrying a large current. A tube of this nature has application, for example, in control of illumination, where it is desired that lights be turned on when the level of illumination in a room becomes too low. It is also adaptable for use in door openers, burglar alarms, smoke alarms, etc.

The cathode 413 or 513 may be constituted of thermally-responsive material, not necessarily bimetallic. It may, for example, be constituted of a material that changes resistance with temperature. A device of this character may thus be employed to perform useful electrical operations by virtue of such resistance changes.

According to tube construction, electrode spacing, gas pressure, etc., the grid may be designed to operate at either a positive or a negative bias, although a positive bias is preferred.

According to the modification of Fig. 2, the cathode 413 is shown connected in circuit with the battery 20 and a ballast resistor 418, so as to impress a potential upon the anode 417 positive with respect to the cathode. The anode potential should be adjusted or regulated to a control value corresponding to the level of the illumination at which it is desired to operate the tube; that is, just below the level at which a discharge occurs in the tube when a low level of light or other radiant energy excites the photosensitive cathode.

If this energy level should rise, upon the application of more light or other radiant energy, a discharge will occur.

Though the tube of Fig. 2 is unprovided with a grid, the element 413 constitutes a cold cathode made of photosensitive material. The control of the discharge may here, too, therefore, be likened to the control exerted by a grid, though the discharge is initiated by the action of light upon the cathode 413, rather than through control secured by the action of light on a grid or similar control element.

This tube has applications similar to those of the tube in Fig. 1. Though simpler and cheaper, these advantages are counterbalanced by shorter life. The tube, however, is capable of handling relatively large amounts of current.

The grid potential may be adjusted to vary the setting for the degree of illumination desired, thus producing break-down of the gas in the tube at the desired point.

According to the present invention, therefore, the starting and stopping, or the control, of the gaseous discharge may be effected by the insertion, in the space of the tube, of an element that is photosensitive, or coated with a photo-emissive material that, upon being subjected to light or other radiant energy, will emit electrons that will cause fields to be set up.

Modifications will occur to persons skilled in the art and all such are considered to be within the spirit and scope of the invention, as defined by the appended claims.

What is claimed is:

1. In combination, a gas-containing tube having two electrodes, namely, an anode and a photo-sensitive electron-emitting cathode, and having also a third electrode, cooperating contact members carried by the cathode and the third electrode, means for connecting a load circuit to the cathode and the third electrode, means for applying a voltage across the cathode and the anode, and means for regulating the voltage to a critical value corresponding to a level of illumination on the cathode such that the cathode shall respond to emit sufficient electrons for initiating a gaseous discharge between the anode and the cathode, thereby to produce positive ions for striking the cathode to heat it, and the cathode being deformable in response to heat to effect actuation of the contact member carried thereby with respect to the other contact member, thereby to control the load circuit.

2. In combination, a gas-containing tube having two electrodes, namely, an anode and a photo-sensitive electron-emitting cathode, and having also a third electrode, cooperating contact members carried by the cathode and the third electrode, means for connecting a load circuit to the cathode and the third electrode, means for applying a voltage across the cathode and the anode, and means for regulating the voltage to a critical value corresponding to a level of illumination on the cathode such that the cathode shall respond to emit sufficient electrons for initiating a gaseous discharge between the anode and the cathode, thereby to produce positive ions for striking the cathode to heat it, and the cathode being bimetallic in order that it may respond to heat to effect actuation of the contact member carried thereby with respect to the other contact member, thereby to control the load circuit.

3. In combination, a gas-containing tube having two electrodes, namely, an anode and a photo-

sensitive electron-emitting cathode, and having also a third electrode and a control electrode, co-operating contact members carried by the cathode and the third electrode, means for connecting a load circuit to the cathode and the third electrode, means for applying a voltage to the anode, means for applying a voltage to the control electrode, means for regulating the control-electrode voltage to a critical value corresponding to the level of illumination on the

5 cathode at which a gaseous discharge shall take place between the anode and the cathode, thereby to produce positive ions for striking the cathode to heat it, and the cathode being deformable in response to heat to effect actuation of the contact member carried thereby with respect to the other contact member, thereby to control the load circuit.
